UNITED STATES PATENT OFFICE.

WILLIAM P. BETTENDORF, DECEASED, LATE OF BETTENNE RF, IOWA, BY JOSEPH W. BETTENDORF, ADMINISTRATOR, OF BETTENDORF, IOWA.

METAL UNDERFRAME CONSTRUCTION FOR CARS.

1,062,690.

Specification of Letters Patent.

Patented May 27, 1913.

Original application filed May 23, 1910, Serial No. 562,922. Divided and this application filed April 25, 1912. Serial No. 693,085.

To all whom it may concern:

Be it known that WILLIAM P. BETTENDORF, deceased, late a citizen of the United States, residing at Bettendorf, in the county 5 of Scott and State of Iowa, did invent certain new and useful Improvements in Metal Underframe Construction for Cars, of which the following is a full, clear, and exact description.

10 This invention relates to underframes for cars, particularly to metal underframes, and the subject-matter thereof has been divided out of the application of said WILLIAM P. BETTENDORF, (deceased), filed May 15 23d, 1910, Serial Number 562,922, for improvement in means for cushioning railway car bodies.

15 The object of said invention is to simplify the construction of the underframe, and at the same time reduce its cost, particularly in so far as the labor involved is concerned, without detracting from either its strength or durability. These objects are accomplished by the means hereinafter fully described, and as more particularly pointed out in the claims.

20 In the drawings: Figure 1 is a side elevation of a broken away end of a car embodying the invention. Fig. 2 is a transverse 30 vertical section of the same taken on line 2-2, Fig. 1, and drawn to a slightly enlarged scale. Fig. 3 is a plan view of the center-sill with the car-body removed. Fig. 4 is a side elevation of the opposite end 35 portions of the center-sill, the right hand end being made in section to disclose the interior arrangement of the draft-rigging and its receptacle. Fig. 5 is a transverse section of the center-sill.

40 For convenience of explanation, the invention is shown as applied to a tank-car, although it will be understood that, with very slight modification or variation in construction, the improvements can be applied 45 to a car having a flat bottom whether it be of the freight or passenger type of cars.

50 Referring to the drawings, A represents a center-sill consisting of a single I-beam, extending from end to end of the car, and 55 arranged so that the web connecting the flanges a, a, thereof is in a horizontal plane. The relative dimensions of this I-beam may be as shown in the drawings, or of any other suitable dimensions. Near its ends this

center-sill has suitable transverse cast metal 55 body-bolsters 2, 2, secured to it, which bolsters are of the tip type, that is they have their central portion in a lower horizontal plane than their end portions, substantially as shown in Fig. 2 of the drawings. Suitable corrugated seats or bearings 3 and 4, 4, are made respectively in the central and end portions of the body-bolsters to accommodate rollers 5, and 6, 6, respectively.

55 The tank 7 here illustrated is preferably 60 of the usual type and has a bearing-plate 8 secured to its under side in the transverse vertical plane of the bolsters, which plate has corrugations on its under side that correspond substantially to the corrugations in 65 the body-bolsters and are in alinement therewith and afford an upper and lower bearing for rollers 5. On each side of these center-plates the tank is provided with suitable side-plates 9, 9, that have suitable triangular-shaped portions depending therefrom, on the undersides of the webs connecting which are formed corrugated seats or bearings 10, 10. These seats or bearings 70 75 80 10, preferably, aline with and correspond in shape to the opposing bearing 4 in the upper surface of the bolster ends, and afford an upper bearing surface for rollers 11, interposed between the same.

85 The body-bolsters are secured directly to the center-sill, and have the central portion of their under sides removed to permit the passage therethrough of the single I-beam center-sill and the contours of this removed portion conform to the shape of the upwardly projecting flanges of the I-beam. The underside of the I-beam center-sill, in the transverse plane of the body-bolsters, is provided with fillers 12, consisting, preferably, of a cast metal plate that extends from 95 flange to flange of said center-sill, and has an integral center bearing-member 13 at its center of length, that is adapted to seat in an oppositely formed socket 14 in the upper surface of the lower center bearing-plate 15 100 secured on the upper surface of the truck-bolster 16 (shown in dotted lines in Fig. 2).

105 The ends of the single I-beam center-sill extend, preferably, beyond the ends of the car-body or tank and at the ends of the beam, and between the upper flanges a thereof, a rectangular cast-metal frame or draft-rigging receptacle B is secured to and sup-

ported upon the web. This draft-rigging receptacle is provided with a central rectangular chamber *b*, which is, preferably, wider than it is long and has its ends transverse to the sides of the sill. The follower-plates *C, C*, of the draft-rigging engage the ends of said chamber, and are retained therein by metal strips *c, c*, and parallel coil-springs *D, D*, are interposed between the ends of 5 said plates *C*. A channel *d* is made in this holder between the chamber *b*, and the end thereof, terminating adjacent to the end of the sill which is of sufficient width and depth to accommodate the short draw-bar 10 *E* of the coupler *F*, and the rear end of said draw-bar has a yoke *G* of the usual construction secured thereto. A suitable recess *e* is made in the rear wall of said chamber that permits the limited reciprocal movement 15 of the yoke. The entrance of channel *d* has a cross-piece *f* bridging it, whose ends are seated in suitable depressions and bolted or riveted in place, and the remainder of the holder, outside of chamber *b* and passage *d* 20 is cut-away down to the base thereof and provided with transverse and longitudinal walls that give it a reticulated appearance from above. The base-plate of said holder extends beyond the rear transverse wall of 25 the same, and a series of longitudinally disposed triangular brace-walls *g* transmit the buffing strain, to which the draft-rigging subjects the holder, to the rear extension of said base-plate, which latter is securely fastened to the web of the center-sill by rivets, as shown, or otherwise. It is obvious that 30 other types of draft-rigging than that shown in the drawings, may be employed that could be secured direct to the ends of the horizontally disposed single center-sill. It is preferred that the draft-rigging hereinbefore 35 described be employed.

What is claimed as new is:

1. An underframe for cars comprising a 40 single I-beam, the web of which is horizontally disposed, and a draft-rigging recep- 45

tacle and follower-stops mounted on and secured directly to each end of the web thereof.

2. An underframe for cars comprising a 50 single I-beam, the web of which is horizontally disposed extending from end to end of the car, and a draft-rigging receptacle and follower-stops secured direct to the ends thereof between its upper flanges. 55

3. An underframe for cars comprising a 60 single I-beam, the web of which is horizontally disposed extending from end to end of the car past the bolsters with its flanges and web intact from end to end, and a draft-rigging receptacle and follower-stops secured direct to the end portions of said center-sill between its flanges.

4. An underframe for cars comprising a 65 single I-beam the web of which is horizontally disposed, a cast-metal draft-rigging receptacle and follower-stops secured to the web of the end portions thereof and provided with a chamber therein for the draft-rigging and with a passage connecting said 70 chamber to the front end of the receptacle, and with a recess in the transverse wall of said chamber opposite said passage, a basal flange extending from the rear transverse wall of said chamber, and braces connecting 75 said rear wall and flange.

5. An underframe for cars comprising a 80 body-bolster near each end thereof, a rolled metal beam center-sill so disposed that its web is horizontal and which connects said body-bolsters, and an integral draft-rigging receptacle and follower-stops secured directly to the ends of the web of said center-sill.

In witness whereof I have hereunto set 85 my hand this 20th day of April, 1912.

JOSEPH W. BETTENDORF,
Administrator of the estate of William P.
Bettendorf, deceased.
